UNITED STATES PATENT OFFICE.

JULIUS DORNETH, OF KONRADSHOHE, NEAR TEGEL, GERMANY, ASSIGNOR TO THE FIRM TYPOGRAPH GESELLSCHAFT M. B. H., OF BERLIN, PRUSSIA, GERMANY.

MATRIX BAR.

Application filed April 7, 1924. Serial No. 704,884.

To all whom it may concern:

Be it known that I, JULIUS DORNETH, engineer, a citizen of Germany, and residing at Konradshohe, near Tegel, Germany, have 5 invented certain new and useful Improvements in Matrix Bars, of which the following is a specification.

The subject of this invention is a two-part matrix bar for matrix setting and line casting machines, the parts of which bearing the characters and the suspending eye respectively are slidable with respect to one another and are guided relatively by means of slots and pins. As regards durability 10 the constructional form, which has hitherto proved to be the best, is that in which one of the parts is milled out from the top and from one of the narrow sides, so that in cross-section it forms a U-shaped groove for 15 guiding the other part. It has, however, been found that even this form of construction, more particularly in the case of small characters, is too thick, as at the connecting place there are three thicknesses next to one 20 another. It is of course possible to form a guide with slots and pins, in which there are only two thicknesses, but hitherto it has not been possible to make this constructional form strong enough, as the pins must fit so 25 accurately in the slots that the parts shall neither move relatively to one another in the direction of their planes nor be capable of separating from one another.

The present invention renders it possible, 30 by the provision of a guiding pin and a slot on each of the two parts, which are slidable relatively to one another, to obtain sufficient rigidity with only two thicknesses.

In the accompanying drawing a constructional form of the invention is shown to an 35 enlarged scale.

Figs. 1 and 2 being two views of the

matrix bar pushed together and extended and

Fig. 3 a longitudinal section on line A—B 45 of Fig. 2.

a and b are the two relatively slidable parts, of which the part a carries the suspending eye and the part b the characters. The part a is provided with a guiding slot e 50 and on its under side with a guiding pin d, while the part b is similarly provided with a pin c and a guiding slot f. When the matrix bar is extended as in Fig. 2, the pins c and d are sufficiently far apart to withstand the 55 stresses occurring with the parts in this position. The more the two parts of the bar are pushed together, the greater will be the distance between the two pins (see Fig. 1) and the less will be the danger of the 60 parts being displaced relatively to one another in their plane and of their being separated one from another.

Obviously the pin d on the part a might 65 be above the slot e and conversely the pin c on the part b might be below the slot f. In this case the distance between the pins would be the greatest, when the bar is extended.

Having now particularly described and 70 ascertained the nature of my said invention and in what manner the same is to be performed, I declare that what I claim is:—

In a matrix bar, a part bearing the characters, and a second part bearing the suspending eye, each of the two parts being provided with a guiding slot and a pin for the pin and guiding slot of the other part. 75

In testimony whereof I hereunto affix my signature in the presence of two witnesses.

JULIUS DORNETH.
